ATTACHMENT FOR PRINTING PRESSES

Don R. Donnell, Los Angeles, Calif.

Application August 27, 1947, Serial No. 770,815

4 Claims. (Cl. 164—98)

1

This invention relates generally to an improved printing press attachment and more particularly to the provision of means which can be readily incorporated into the usual platen printing press and use of which will enable the ready cutting and perforating of paper and printed material in a very simple manner.

A primary object of the invention is to provide a sturdy perforating or cutting rule for use with a platen press which is of simple construction, may be easily installed and which will not interfere with the operation of the inking rollers and will furthermore prevent damage to the rollers.

A second object of the invention is to provide a perforating or cutting means which will be easily removable from the perforated surface upon completion of the perforating operation.

Yet a further object of the invention is to provide perforating means for printing presses or the like which may be easily adjusted transversely and which furthermore is provided with means for angular adjustment with respect to the platen.

Other and further important objects of this invention will be apparent from the disclosures in the accompanying drawings and the following specification.

The invention, in a preferred form, is shown in the drawings and hereinafter more fully described.

In the drawing:

Figure 1 is an elevation of the improved printing press attachment of this invention, showing the same as associated with the platen.

Figure 2 is an enlarged view of the perforating rule showing more clearly the details of its construction.

Figure 3 is a cross-sectional view taken on the line 3—3 of Figure 2.

Figure 4 is a sectional view taken on the line 4—4 of Figure 2 indicating more clearly the structural relationship between the perforating rule, its base plate, and the gripper bar.

Figure 5 is a view, partially in section, taken on the line 5—5 of Figure 2 showing details of construction of the perforating blade with respect to the rule.

Figure 6 is a plan view showing the first step of the method of operation.

Figure 7 is a similar view showing the next step in the method of operation.

Figure 8 is a further plan view showing the third step in the method of operation.

Figure 9 is a cross-sectional showing taken on the line 9—9 of Figure 8.

As shown in the drawing:

2

Referring specifically to Figure 1 the numeral 11 indicates generally the platen of a printing press to which is connected the normal type of gripper bar 13. The gripper bar 13 for the purposes of this invention is modified to provide a longitudinal slot 15 and a longitudinal indentation 17 extending across its lowermost edge.

The perforating or cutting bar indicated generally by the numeral 19 has a cut-down portion 10 at its lower extremity which is adapted for insertion in a recess 23 of the base plate 25. An ordinary bolt 27 is adapted for insertion in a hole 29 in the base plate 25 and extends through the longitudinal slot 15 of the gripper bar 13. The hole 29 overlaps the recess 23 in the base plate and a matched indentation 31 is provided in the cut-down portion 21 of the perforating rule whereby insertion of the bolt 27 will prevent longitudinal slipping of the perforating rule 19 with respect to the base plate 25, this in addition to maintaining the gripper bar 13, the base plate 25, and the perforating rule 19 in fixed relationship. It will be seen that when the bolt 27 is loosened the perforating rule 19 may be adjusted 20 transversely to any desired position. Angular adjustment may also be obtained when the bolt 27 is loosened by the turning of screws 33 and 35 which are mounted at the lower extremity of the base plate 25 and whose heads engage the longitudinal indented portion 17 of the gripper bar 13.

The perforating blade 37 is held stationary in the longitudinal slot 39 of the perforating rule 19 by application of small holding screws 41. The slot 39 engages the blade 37 snugly at its lower extremity, but flares outwardly at its open end as is clearly illustrated in Figure 3.

Referring specifically to Figures 6, 7, and 8, the method of operation consists of the placement of parallel strips 43 of adhesive material upon the tympan paper 45 mounted on the platen 11. Thereafter the next step consists in the positioning of two adjacent pieces 47 of string, cord, or wire between adhesive strips 43, the adjacent pieces then being held in such applied position by small pieces of adhesive 49. The third step comprises the positioning of a strip 51 of zinc, lead, or other soft metal upon the juxtaposed pieces of cord 47 and the subsequent fastening 50 of same in some suitable manner.

The positioning of the cord 47 and piece of metal 51 will be such on the platen 11 that the descending blade 37 of the perforating rule 19 will encounter the tympan paper 45 between the two pieces of cord 47. The blade 37 will have no

difficulty in piercing the piece of soft metal 51, but after the perforation of the paper on the tympan 45, the metal will tend by spring action to force the blade away from the perforated material and therefore not disturb its position on the tympan 45. The shape assumed by the piece of metal 51 is demonstrated clearly in Figure 9 and the above-described action will be made obvious by this showing. It will further be understood that the joined action of the adjacent pieces of cord 47 with the flared portion of the blade slot 39 will tend to stretch the material to be perforated immediately prior to the perforating action whereby such action will be facilitated. Although the paper will receive positive perforations, the projection of the cutting blade 37 will be insufficient to injure the heavy tympan paper 45.

I am aware that many other changes suggested by my invention may be made and wide variations obtained without departing from the spirit of my invention and I do not wish therefore to be limited to the particular disclosures herein described, but give reference to the appended claims.

I claim:

1. A printing press attachment comprising a perforating gripper, a base plate removably mounted on the gripper bar of the press and rigidly connected to said perforating gripper, means for angular adjustment of said base plate with respect to the gripper bar of the press longitudinal slots in said perforating gripper, a cooperative perforating element on the platen of the press, and means for transverse adjustment 30 of the base plate on said gripper bar.

2. A printing press attachment comprising a perforating gripper, a base plate removably

5 mounted on the gripper bar of the press and rigidly connected to said perforating gripper, and means for angular adjustment of said base plate with respect to the gripper bar of the press, said 10 means comprising two screws mounted in said base plate whose heads contact the gripper bar of the press, longitudinal slots in said perforating gripper, a cooperative perforating element on the platen of the press, said element comprising two juxtaposed lengths of cord aligned with said longitudinal slots and a strip of soft metal superimposed on the cords.

3. A printing press attachment comprising a 15 perforating gripper mounted on the gripper bar of the press, longitudinal slots on said perforating gripper on each side of the blade thereof, and a cooperative perforating element on the platen of the press.

4. A printing press attachment comprising a 20 perforating gripper mounted on the gripper bar of the press, longitudinal slots on said perforating gripper on each side of the blade thereof, and a cooperative perforating element on the platen of the press, said element comprising two juxtaposed lengths of cord aligned with said longitudinal slots and a strip of soft metal superimposed on said cords.

DON R. DONNELL.
